David Hathaway of Troy, New York
Assignee to
Loy, Richardson and Boynton of the same place
Letters Patent No. 826, Dated August 19th 1856.

The schedule referred to in this letter is Patent and making part of the same.

To all whom it may concern:

Be it known that I, David Hathaway of Troy in the County of Rensselaer and State of New York, have invented or produced a new and original design for a parlor stove, which I call the "Laurel" and I do hereby declare that the following is a full, clear and exact description of the same, reference being had to the annexed drawings forming part of this specification, in which Fig. 1, is a perspective view of the stove, Fig. 2, a view of the fender, and Fig. 3, a view of the top plate.

My design for parlor stove is as follows, viz; A, (Fig. 1,) is the front plate, ornamented with the scroll edges (a) shells (d, d) and ornamental sliding doors (e). B, is the end plate, decorated with the shell (f), panel ornament (g) arched moulding (h, h). C, is the top frame plate, with the shells (i, i) and ornamental moulding (j, j). D, is the bottom plate, with the shell work (k, k) and ornamental moulding (l). E, is the damper plate, F, is the leg with the scrolls (m). G, (Fig. 2,) is the fender with the scroll mouldings (m, m). H, (Fig. 3,) is the top plate decorated with the shells (o, o) scrolls (p, p) and ornamental moulding (q, q.)

Having fully described my design for parlor stove, what I claim as new therein and desire to secure by letters patent, is - The ornamental design and configuration of parlor stove plates, such as herein described and shown in the annexed drawings.
